UNITED STATES PATENT OFFICE.

EMIL A. MELZE, OF CHICAGO, ILLINOIS.

COMBINATION DRAWERS AND SUSPENSORIY.

No. 925,121.

Specification of Letters Patent. Patented June 15, 1909.

Application filed May 23, 1908. Serial No. 434,680.

To all whom it may concern:

Be it known that I, EMIL A. MELZE, a citizen of the United States, residing at Chicago, county of Cook, and State of Illinois, have 5 invented certain new and useful Improvements in Combination Drawers and Suspensoriess, of which the following is a specification.

My invention relates to a combination 10 drawers and suspensoriess, and the object of my invention is to provide a device of the class mentioned, which may be worn with comfort and ease; and in which the suspensoriess portion shall be adjustable to hold the 15 parts with any degree of tightness desired.

A further object of my invention is to provide a combination drawers and suspensoriess in which the drawers shall partake of the ordinary form, and in which the portion of the 20 drawers about the crotch shall form a part of the suspensoriess or receptacle.

Other objects will appear hereinafter.

My invention will be more readily understood by reference to the accompanying 25 drawings forming a part of this specification and in which,

Figure 1 is a detail perspective view of a portion of a pair of drawers equipped to form a device embodying my invention in its preferred form, and Fig. 2 is a section on the line x-x of Fig. 1.

Referring now to the drawings, 1 indicates a pair of drawers of any ordinary or preferred construction, the same being open in 35 front as at 2 in the usual manner. Secured within the drawers is a U shaped member 3 formed of fabric. This may be knitted integrally with the drawers but I prefer to form it of a separate piece of fabric and stitch it in 40 place.

The lower or central part 4 of the member 3 is quite wide or deep in order to form an

ample pocket 5 for the parts and is secured as by stitching to the crotch 6 of the drawers. Extending upwardly from the portion 4 are 45 the long narrow side members 7-7 which are preferably stitched to the drawers, one upon each side of the opening 2. These extend a short distance above the upper edge of the drawers and are provided with the 50 catches 8 by means of which they may be adjustably secured to the suspenderiess; in order to hold the device at a comfortable height.

The stitching preferably extends entirely around the bottom or outer edge of the U 55 shaped member 3 but is discontinued for a short distance upon the upper inner edge adjacent to the lower end of the opening 2 as at 9, forming an inlet or entrance 10 to the pocket 5. It should be noted that the portion 4 is preferably plaited at its forward edge as at 11 to give greater fullness to the pocket.

Having described my invention what I claim as new and desire to secure by Letters 65 Patent is:

A pair of drawers having the front fly in combination with a suspensoriess formed therein, said suspensoriess comprising a U-shaped piece of fabric arranged upon both sides and 70 below said fly and stitched along both its edges to the drawers, the lower portion being enlarged and with the adjacent portion of the drawers forming a pocket, and the stitching being omitted along the inner edge on one 75 side of the fly to leave an opening to the pocket, substantially as described.

In testimony whereof I have signed my name to this specification in the presence of two subscribing witnesses.

EMIL A. MELZE.
